KEYBOARD FOR TYPOGRAPHICAL MACHINES

Filed Sept. 16, 1929

UNITED STATES PATENT OFFICE

SAMUEL E. SPERRY, OF HOLLIS, NEW YORK, ASSIGNOR TO INTERTYPE CORPORATION,
OF BROOKLYN, NEW YORK, A CORPORATION OF NEW YORK

KEYBOARD FOR TYPOGRAPHICAL MACHINES

Application filed September 16, 1929. Serial No. 393,080.

The present invention relates to typographical machines and more especially to those of the general class shown and described in U. S. Letters Patent No. 436,532, granted Sept. 16, 1890, to O. Mergenthaler, wherein matrices stored in a magazine are selectively released by operation of a keyboard controlling matrix delivery escapements, the matrices so delivered being assembled in a line from which a type bar or slug is cast.

The invention relates more particularly to improvements in the keyboard for machines of this general class whereby the banking bar which limits the strokes of the key bars and supports the key bars in horizontal alinement for proper engagement with the cam yoke triggers generally used in such keyboards may be cleaned with facility and thus maintained in proper operating condition.

In order to secure proper operation of a keyboard mechanism of the class referred to, it is necessary to maintain the banking bar and the surface of the key bars engaging therewith, in thoroughly cleaned condition. Obviously, accumulation of dirt or foreign matter, especially on the underside of the banking bar or on the banking surface of the key bars which strike the underside of the banking bar, will cause the key bars to rise to different heights, and further, the key bars which fall by gravity after they are operated, may bind or stick due to dirt accumulation on the underside of the banking bar or the notch of the key bar engaging therewith, and thus result in faulty operation. The key bars are usually constructed to fall by gravity after operation but any slight sticking due to gummed dirt accumulation will prevent them from falling because of the friction and load of cooperating mechanism which their weight must overcome. Notwithstanding the existing necessity for cleaning of the banking bar and key bars in keyboards of this class, the keyboards as heretofore generally used have been built in such a manner that the banking bar is permanently doweled and mounted therein with screws and while the banking bar may be removed with suitable tools, great difficulty would then be encountered because

no provision has heretofore been made for a locking bar to cooperate with a removable banking bar and without such provision, when the banking bar is taken out of place, the key bars will tumble out of engagement with their cooperating mechanism and removal and adjustment of a large portion of the keyboard mechanism would then be necessary to return the parts to their proper place and enable replacement of the banking bar.

The primary object of the present invention is to provide an improved keyboard key bar banking bar which will be easily and quickly removable and replaceable with respect to the rest of the keyboard, to permit cleaning of the banking bar and key bars, without disturbing or requiring dismantling of any of the associated parts of the keyboard mechanism.

Another object of the invention is to provide a novel and improved key bar locking bar which will serve to retain the key bars in proper alinement and register with the associated parts of the keyboard while the key bar banking bar is removed, thereby avoiding displacement of the key bars during cleaning of the banking bar.

A further object is to provide an improved banking bar which may be removably applied to existing keyboards or keyboards such as those heretofore used, without requiring material changes in the construction thereof.

To these and other ends, the invention consists in certain improvements and combinations and arrangements of parts all as will be hereinafter more fully described, the features of novelty being pointed out particularly in the claims at the end of the specification.

In the accompanying drawing:

Fig. 1 is a fragmentary perspective view of the rear portion of the keyboard of a typographical machine embodying the present invention;

Fig. 2 is a detail perspective view showing two of the key bars and their cooperating triggers;

Fig. 3 is a detail perspective view of one end of the banking bar and the cooperating supporting block;

Fig. 4 is a detail view, partly in section, of the banking bar and the side members of the keyboard frame, showing the means for detachably mounting the banking bar in the frame of the keyboard; and

Fig. 5 is a detail perspective view of portions of the banking bar and a side member of the keyboard frame, illustrating modified means for mounting the banking bar.

The invention is shown in the present instance applied to a keyboard of the kind commonly used in typographical machines of the class hereinbefore referred to, these keyboards as heretofore used generally being shown and described for example in U. S. Letters Patent No. 1,092,715, granted April 7, 1914 to T. S. Homans. Since the present invention concerns the key bars and the banking bar and locking bar cooperative therewith, the drawing has been confined mainly to these portions of the keyboard, it being deemed unnecessary to describe in detail the rest of the keyboard construction which is well known to those skilled in the art. It may be described generally however as comprising a frame having upright side members 1 which support at their upper ends a pair of revoluble rollers 2 above which are mounted rows of cam yokes 3 which carry cams 4 which, when the cam yokes are tripped, rest on the respective rollers whereby the cams are caused to revolve and to raise the respective cam yokes, the latter acting on reeds or rods which move upwardly and actuate escapements which control the delivery of the matrices from the magazine.

The tripping of the cam yokes to set the respective cams into operation is controlled by triggers or bellcrank levers 5 on which the respective cam yokes rest, and these triggers are actuated by vertically reciprocating key bars 6 which have notches 6^a in their upper ends to engage the respective triggers, the triggers being usually arranged in two horizontal rows, in front and in rear respectively of the row of key bars, and the notches 6^a in the upper ends of the key bars being arranged in the front and rear edges of the alternate key bars.

The row of key bars themselves are arranged between the side frame members 1 of the keyboard, they being guided at their lower ends by suitably slotted guide plates 7, and the key bars are guided toward their upper ends by the usual slotted guide plate 7^a which extends transversely in front of the key bars and prevents forward or lateral displacement thereof and by a banking bar 8 which is received in a notch in the rear edge of each key bar and limits the strokes thereof, the key bars resting on the banking bar when in their normal lowered positions and the banking bar thus alining the key bars horizontally so that they will be in uniform

operative relationship with the respective triggers.

The banking bar provided by the present invention is indicated at 8, it engaging in notches 9 formed in the rear edges of the key bars, the upper and lower ends of these notches being so spaced that they will engage the upper and lower sides of the banking bar 8 so that the latter will limit the strokes of the key bars and will support the key bars while in their normal lowered position.

The banking bar, instead of being permanently mounted in the keyboard frame is, according to the present invention, removably mounted therein. In the construction shown in Fig. 1, blocks 10 and 10^a are fixed to the upper portions of the keyboard side frame members 1, the block 10 having a notch 11 forming at its inner side and also having a recess 12 formed at its forward side and extending outwardly from the notch and the block 10^a having a recess 13 formed in its forward side and extending outwardly from its inner edge. One end of the banking bar 8 has a pin 14 projecting endwise from its upper rear corner which is adapted to be inserted endwise into the recess 13, after the banking bar has been swung to bring the tongue into position to enter said notch, and the opposite end of the banking bar is adapted to enter the notch 11 at the inner side of the block 10, this end of the banking bar having a latch or spring plunger 15 mounted to move endwise therein and to project from this end of the banking bar; a compressed coil spring 16 being mounted in the banking bar behind this latch or plunger, and a knob or projection 17 is provided the stem of which extends through a longitudinal slot 18 in the banking bar and is threaded or otherwise fixed to the plunger 15, the engagement of the stem of this knob with one end of the slot 18 limiting the outward movement of the latch or plunger and thereby preventing its detachment from the banking bar. This latch or plunger is bevelled at its forward side, as shown, so that it will ride on the outer edge of the notch 11 and thereby force the latch into the respective end of the banking bar, thus permitting this end of the banking bar to be swung into the notch 11 in the block 10, and after the banking bar has reached its correct operative position, the latch or plunger 15 will move outwardly under the action of the spring 16 and will engage in the notch 12 in the block 10, the latch or plunger then locking this end of the banking bar in its correct operative position, the opposite end of the banking bar being held in place by the pin 14 engaging in the recess 13. To remove the banking bar, it is only necessary to retract the latch or plunger 15 by pressure upon the knob 17, such retraction of the latch or plunger unlocking this end of the banking bar from the block 10, and to

tilt the lower side of the banking bar rearwardly about the pin 14 as a horizontal axis, the forward upper edge of the banking bar on which the upper ends of the notches 9 in the key bars rest being thereby lowered 5 and allowing the key bars to drop and rest on the guide plate 7, after which the end of the banking bar carrying the latch or plunger may be swung rearwardly about the pin 14 on its opposite end as a center until the latch-carrying end of the banking bar is clear of the block 10 after which the banking bar can be completely removed by withdrawing the pin 14 endwise from the notch 13, and such complete removal of the banking bar enables 15 its front and upper and lower surfaces to be thoroughly cleaned. The banking bar may be replaced in the keyboard by first placing the banking bar approximately in operative position with the pin 14 engaged in the recess 20 13 so that the upper forward corner of the banking bar will enter beneath the upper ends of the notches 9 in the key bars and then tilting the lower edge of said bar forwardly about the pin 14 as a center, thereby causing 25 the upper forward edge of the banking bar to engage the upper ends of the notches 9 in the key bars and to lift all of the key bars slightly to bring them to normal position, after which the end of the banking bar carrying 30 the latch is pushed forwardly into the notch 11, the latch slipping past the corner of this notch and engaging in the recess 12 to lock the banking bar rigidly and non-rotatably in operative position. In order to 35 reduce friction between the key bars and the front face of the banking bar, the latter may be grooved longitudinally, as shown, to provide upper and lower surfaces 19 of reduced area to engage the key bars.

Instead of using a banking bar having a latch or spring plunger for holding it in place, as just described, a banking bar 8^a having a fixed knob 17^a thereon may be used, 45 as shown in Fig. 5, the opposite end of this banking bar being the same as that already described and shown. In this instance, the relatively fixed block 100 is formed with a downwardly and forwardly inclined slot 101 to receive a pin 102 which projects endwise 50 from the upper rear corner of this end of the banking bar in alinement with the pin 14 which projects from its opposite end, the end of the banking bar carrying the pin 102 being notched at its forward side, as at 8^b 55 to receive the adjacent corner of the respective side member of the keyboard frame, and a locking lever 103 is pivoted at 104 on the block 100, it allowing the banking bar to be tilted or rocked about the pins 14 and 102 as a horizontal axis to allow the key bars to drop, as indicated by the full lines in Fig. 5 and then swinging rearwardly for removal, the pin 102 riding upwardly and out of the 60 slot 101, while the lever 103 occupies the full

line position shown, and acting, when swung into the dotted line position shown, to lock the banking bar in operative position after the banking bar has been applied and tilted or rocked about a horizontal axis from the full line to the dotted line position to slightly raise the key bars as previously explained respecting the construction shown in Figs. 1 to 4 inclusive, a detent pin 105 being preferably provided in the banking bar to retain the lever 103 in locking position.

In order to prevent accidental displacement of the key bars which have the notches 6^a in their forward sides to receive the triggers 5, when the banking bar is removed from the keyboard, a key bar locking bar is provided which will not only serve to lock the key bars against actuation when such is desired but will also serve to retain the key bars in place after the banking bar has been removed. This improved locking bar according to the present invention comprises an angle iron member 23 having horizontal and vertical flanges 24 and 25 extending in right angular relation, and having pivots 26 extending from its opposite ends in substantial alinement with the apex formed between its flanges and bearing rotatably in the blocks 10 and 10^a respectively, this locking bar being tilttable about its pivots so that it may occupy either the full or the dotted line position shown in Figure 1. The lower edge of the vertical flange 25 of the locking bar is arranged to rest on the shoulders 27 formed on the key bars when the locking bar is in its locking position shown by the full lines in Fig. 1 it then locking all of the key bars against actuation, and the forward edge of the horizontal flange 24 of the locking bar is adapted to bear against or to remain in close proximity to the vertical edges 28 formed on the key bars above the shoulders 27, so that the horizontal flange 24 of the locking bar will prevent rearward tipping or displacement of any of the key bars while the banking bar is removed for cleaning, whether the locking bar is in its locking position shown by the full lines or in the unlocked position as shown by the dotted lines in Fig. 1.

It will be understood that the key bars are shifted upwardly when actuated by key levers one of which is provided for each key bar, one of these key levers 29 being shown in the present instance, it having a lug on its rear end which engages in a notch 30 in the respective key bar, the key lever being pivoted in the keyboard at 31 and provided with a button or finger piece 32, the key bars all resting normally on the banking bar but moving upwardly under the action of the respective key levers and thereby tripping the respective triggers and setting the corresponding cams into operation to effect the release of the matrices from the magazine. The locking bar may be rocked about its

5 pivots 26 to bring it into locking or unlock-
ing position by a lever 33 at one side of the
10 keyboard, the rear end of this lever being
fixed by the screw 34 to the locking bar 23
so that swinging of this lever upwardly into
the full-line position will set the locking bar 23
15 in locking position and lowering of this lever
to the dotted line position will set the locking
bar in unlocking position relatively to the key
20 bars.

19 I claim as my invention:—

21 1. In a keyboard embodying a frame con-
taining a row of vertically reciprocatory key
bars, a banking bar having means for sup-
25 porting it to tilt on a horizontal axis into and
out of supporting relation with the key bars,
and means for removably securing the bank-
ing bar in operative position in the keyboard
28 frame.

29 2. In a keyboard embodying a frame con-
taining a row of reciprocatory key bars, a
banking bar cooperative with the key bars, to
33 support them in common alinement, the bank-
ing bar having means supporting it on the
37 keyboard frame to tilt on a horizontal axis
to lower and raise the key bars, and means
41 for rigidly securing the banking bar to the
45 keyboard frame.

49 3. In a keyboard embodying a frame con-
53 taining a row of vertically reciprocatory key
bars, a banking bar cooperative with the key
57 bars to normally support them in common
61 horizontal alinement, one end of the banking
65 bar having means to tiltably and detachably
engage the keyboard frame, and a retractable
69 plunger to detachably connect the opposite
73 end of the banking bar to the keyboard frame.

77 4. In a keyboard embodying a frame con-
81 taining a row of vertically movable key bars,
85 a banking bar cooperative with the key bars
89 to normally support them in common aline-
93 ment, and means for detachably securing the
97 banking bar to the keyboard frame comprising
101 blocks fixed to the sides of the keyboard
105 frame and having recesses therein, one end
109 of the banking bar having a pin to tiltably
113 engage in the recess of one of said blocks, and
117 a latch carried by the opposite end of the
121 banking bar and engageable in the recess in
125 the other block.

133 5. In a keyboard embodying a frame con-
137 taining a row of reciprocatory key bars, a
141 banking bar cooperative with the key bars
145 to aline them, one end of the banking bar
149 having means for movably connecting it to
153 the keyboard frame, and a latch carried by
157 the opposite end of the banking bar and co-
161 operative with the keyboard frame to remov-
165 ably secure the banking bar in operative
169 position therein, said latch having a projec-
173 tion thereon for retracting it.

177 6. In a keyboard embodying a frame con-
181 taining a row of reciprocatory key bars, a
185 banking bar removably attached to the key-
189 board frame and normally cooperative with

193 the key bars to aline them, and a locking bar
197 movable into locking and unlocking relation
201 with the key bars, said locking bar being in
205 cooperative relation with the key bars while
209 in locking and unlocking positions to main-
213 tain the key bars in alinement while the bank-
217 ing bar is removed.

221 7. In a keyboard embodying a frame con-
225 taining a row of reciprocatory key bars, a
229 banking bar removably attached to the key-
233 board frame and normally cooperative with
237 the key bars to maintain them in alinement,
241 and a locking bar pivoted in the keyboard
245 frame and having a flange movable into and
249 out of locking relation with the key bars and
253 having another flange extending at an angle
257 to the first mentioned flange and engageable
261 with the key bars while the locking bar is in
265 locking and unlocking relation with the key
269 bars to maintain the key bars in alinement
273 while the banking bar is removed.

277 In testimony whereof I have hereunto set
281 my hand.

285 SAMUEL E. SPERRY.
